UNITED STATES PATENT OFFICE.

JOSEPH EDWARD JOHNSON, OF MERIDEN, CONNECTICUT, ASSIGNOR TO CONNECTICUT TELEPHONE & ELECTRIC COMPANY, INC., OF MERIDEN, CONNECTICUT, A CORPORATION OF CONNECTICUT.

BREAKER-ARM FOR IGNITERS.

1,266,811.

Specification of Letters Patent. Patented May 21, 1918.

Application filed January 20, 1917. Serial No. 143,456.

To all whom it may concern:

Be it known that I, JOSEPH EDWARD JOHNSON, a citizen of the United States of America, residing at Meriden, New Haven county, Connecticut, have invented a new and useful 5 Breaker-Arm for Igniters, of which the following is a specification.

My invention relates to improvements in so-called igniters for internal combustion 10 engines and consists principally in improving the breaker arm construction whereby greater efficiency is obtained, particularly for high speed work. Further, the structure has advantages from the stand-point of 15 economy of manufacture as well as durability.

In the drawings:

Figure 1 is a plan view of my improved breaker arm with certain associated parts.

20 Fig. 2 is a perspective view of the breaker arm relatively enlarged.

Fig. 3 is a plan view of a blank from which the breaker arm is formed.

The breaker arm when viewed from above 25 is shown to be curved. One end thereof is mounted on a pivot 1, the other end carrying the contact point 2. 3 conventionally represents a cam, the point of which intermittently engages the arm to rock it on its 30 pivot 1. To reduce wear the arm may be provided intermediate its length with an anti-friction roller 4. 5 represents a fixed contact point which is arranged to be intermittently engaged by the point 2, making 35 and breaking of the contact between said points being determined by the cam 3. 6 is a spring which may bear against a suitable abutment 7, said spring operating in a direction to bring the point 2 against the 40 point 5. The breaker arm 8 is constructed as follows: It comprises two spaced curved or substantially C-shaped arms or side plates 8-8, which are integrally united at 9. The breaker arm may be made in a single piece 45 of sheet metal blank of approximately the outline indicated in Fig. 3. This blank may have an aperture 10 for receiving the point 2 which likewise has two slotted portions 11-11 adjacent to the aperture 10 so that 50 when the blank is folded into the final form it will produce an arm, the upper end of which is skeletonized so as to tighten the weight thereof very greatly, whereby its rapid action may be made much more cer-

tain. 12-12 are apertures in the blank 55 which are designed to receive the pivot pin 13 for the antifriction roller 4. At one side of the blank and on the inner border, I may also form an integral arm 14, the function of which will be later described. 15-15 are 60 two apertures at the ends of the blank which may receive a bushing 16, the ends of which may be formed to properly space the side portions 8-8 and to hold them in the proper relation. The arm 14 is located between the bushing 16 and the pivot pin 13 and this arm is off-set or bent so as to project across the space between the two arms 8-8, as best seen in Fig. 2, thereby forming an abutment to which the inner end of the 70 spring 6 may be connected, for example, by means of a rivet 17. The spring 6 is preferably formed of bronze so as to constitute a good conductor and if desired this spring 6 may be reinforced or backed by a secondary 75 spring of steel indicated at 6a.

By the above arrangement the various parts may be rapidly produced and assembled for use, and in use the breaker arm may be employed with great efficiency and in high 80 speed motors in connection with ignition apparatus for use in high speed motors. By skeletonizing the upper end of the arm, and by doing this in such a way that there is no sacrifice of strength, the arm may be 85 very rapidly vibrated to effect with certainty the desired make and break connection when the device is used in high speed service. It will be apparent that the slotting or perforating of the generally curved 90 or arched breaker arm plates forms an integral arched truss-like structure at the outer end of the breaker arm which affords adequate strength and rigidity, at the same time so lightening the arm at the end where 95 the greatest movement occurs that its operative speed may be increased without sacrifice of efficiency. Another advantage resulting from this construction is that by reason of the extreme lightness of the upper end 100 of the arm the wear on the cam and contact block or roller 4 is substantially reduced, thereby increasing the effective life of the device.

What I claim is:

1. Interrupter mechanism for high speed igniters comprising, a breaker arm of generally arched formation arranged to be piv-

105

totally supported at its inner end and provided with a contact bearing portion at its outer end, said arched breaker arm having a longitudinally extending slot therein disposed between the edges of the arm and extending to a point short of the contact bearing end thereof to lighten the arm and to provide a truss-like structure at the outer end thereof.

2. Interrupter mechanism for high speed igniters comprising, a breaker arm of generally arched formation comprising two rigidly connected but spaced plates arranged to be pivotally supported at its inner end and provided with a contact bearing portion at its outer end, a longitudinally extending slot in each of said plates disposed between the edges thereof and extended to a point near the contact bearing end to lighten the arm and provide an integral truss-like structure at the outer end thereof.

3. A breaker arm for high speed igniters comprising, a pair of spaced rigidly con-

nected curved sheet metal plates, a pivotal bearing at its inner end, said bearing serving to space said plates, a contact carrier 25 at the outer end also operating to space said plates, a lug formed integrally with one plate and bent angularly into the space between the plates, a contact spring rigidly secured to said lug and operating to carry 30 current and to swing said arm in one direction.

4. A breaker arm for high speed igniters comprising a pair of spaced rigidly connected curved sheet metal plates, a pivotal 35 bearing at one end serving to space said plates, a contact carrier at the other end also serving to space said plates, an intermediate anti-friction roller bearing substantially midway of the length of said plates, 40 that part of each plate between said roller bearing and the contact carrier being perforated along the median line.

JOSEPH EDWARD JOHNSON.
